UNITED STATES PATENT OFFICE.

WALTER T. GORDON, OF CHICAGO, ILLINOIS.

COLLAR-FASTENING CLIP.

No. 905,418.

Specification of Letters Patent.

Patented Dec. 1, 1908.

Application filed May 28, 1906. Serial No. 319,081.

To all whom it may concern:

Be it known that I, WALTER T. GORDON, a citizen of the United States, of Chicago, in the county of Cook and State of Illinois, have invented certain new and useful Improvements in Collar-Fastening Clips; and I do hereby declare that the following is a full, clear, and exact description thereof, reference being had to the accompanying drawings, and to the letters of reference marked thereon, which form a part of this specification.

This invention relates to a novel fastening device, in the nature of a clip for fastening a collar to the shirt-band, and the invention consists in the matters hereinafter set forth and more particularly pointed out in the appended claims.

In the drawings:—Figure 1 is a perspective view of the band of a shirt and a collar thereon, fastened at the back by a novel clip. Fig. 2 is a section, taken on line 2—2 of Fig. 1. Fig. 3 is a perspective view of the form of clip shown in Figs. 1 and 2. Fig. 4 is an edge view of the clip.

My novel collar fastening clip is designed for use in connection with a shirt-band composed for a part of its length of two folds and wherein the button-hole at the back of the shirt-band to receive the collar button or other fastening device is formed in the outer fold of the band, the inner fold protecting the neck of the wearer from contact with the collar button. The said outer band is free at its lower margin and the collar button or fastening device when inserted in place is passed beneath the lower margin of the rear or free fold and inserted into the button-hole from the rear of said fold. In some instances, the rear fold of the band is stitched to the front or main fold except at the button-hole thereby forming a pocket to receive the collar button or fastening device.

My novel clip comprises a body portion that occupies the space between the folds of the neck-band above the button-hole and a tongue that extends rearwardly through the button-hole and projects with its free end downwardly therefrom in position to pass through the rear button-hole of the collar when the collar is brought to position and pressed upwardly into place. The said tongue, when so engaged with the collar, holds the collar from rising and also holds it from shifting laterally or circumferen-

tially of the shirt-band. Ordinarily there is little or no tendency for the collar to drop downwardly at the back of the shirt-band, inasmuch as the pull or stress exerted by the collar on the rear fastening device is upwardly. If desired, however, a suitable stop may be provided which engages the collar in such manner to prevent depression of the rear side thereof in case such tendency should occur.

As shown in said drawings, A A¹ designate the inner and outer folds of the shirt-band and B the collar, consisting, in this instance, of a double fold or turn-down collar, and C my novel fastening clip. The said clip comprises an elongated transverse main or body portion c, a central, downwardly extending tongue, and two arms or lugs c² c² extending downwardly from the body portion, one at each side of the central tongue.

The clip is inserted in place by first inverting it with the tongue directed upwardly, inserting the tongue upwardly between the two folds of the neck-band and through the button-hole of the fold A¹ of said neck-band from the rear thereof, and thereafter reversing the clip endwise so as to bring the transverse body portion c into the space between the folds of the neck-band above the button-hole, and the central collar holding tongue with its end pointed downwardly, outside of the rearmost fold of the shirt-band. When the clip is thus inserted into place and as it is being reversed to bring it to its proper position the ends of the side arms or lugs c² are passed over and in contact with the rear face of the outer fold of the neck-band near the margin thereof, which margin, by reason of its flexibility is, at this time, turned outwardly, and when the clip is completely reversed and assumes its final or operative position as shown in Figs. 1 and 2, the said arms or lugs c² lie in rear of the outer fold of the neck-band. The said arms tend to give lateral stability to the clip when in place and avoids tendency of the clip twisting, and this function of the arms is emphasized when the collar is in place with its inner fold b inserted partially between the said arms and the central tongue, as clearly indicated in Figs. 1 and 2. The said central tongue is curved or sprung outwardly or rearwardly from the transverse body portion c in order to afford room for the ready fitting of the collar to the clip. Preferably

also the lower end of the central tongue is curved outwardly as indicated at c^3 , so as to facilitate the insertion of the tongue into the button-hole of the inner fold of the collar when the collar is fitted in place.

In order to prevent the collar dropping or falling from its position on the shirt-band in the event that such a tendency should occur, I may provide a stop at the lower end of the tongue c^4 constructed and arranged to engage the lower margin of the inner fold of the collar. In the present instance such shoulder or stop is provided by cutting and bending the tongue to form an inwardly projecting spur c^4 located on the inner side of the tongue. The spur thus formed is severed from the body of the tongue at its upper margin and is inclined upwardly and rearwardly from its lower end, thus producing an abrupt, upwardly facing shoulder at its top, approached by a gradual inclination of the spur, which affords no obstruction to the fitting of the collar to the tongue, while preventing the collar dropping as stated.

A general advantage secured by the use of my novel clip is its compactness and the little space which it occupies. The device presents no projections, as in the case of an ordinary collar button, tending to press uncomfortably against the neck of the person wearing the same. Another advantage of the device is the great economy in which it may be manufactured, such manu-

facture embracing very simple stamping and swaging operations.

I claim as my invention:

1. A one-piece sheet-metal clip for fastening a collar to a two-fold shirt-band, comprising an elongated transverse body portion, a centrally disposed downwardly extending collar attaching tongue, and two arms extending downwardly from the ends of said body portion, one at each side of the tongue, said tongue being downwardly and rearwardly curved from the points where it joins said body portion.

2. A one-piece sheet-metal clip for fastening a collar to a two-fold shirt-band, comprising an elongated transverse body portion, a centrally disposed downwardly extending collar attaching tongue, two arms extending downwardly from the ends of said body portion, one at each side of the tongue, and a projection extending inwardly from the lower end of said tongue, said projection having an abrupt upwardly facing part and an inwardly and upwardly inclined underside.

In testimony, that I claim the foregoing as my invention I affix my signature in presence of two witnesses, this 26th day of May A. D. 1906.

WALTER T. GORDON.
